UNITED STATES PATENT OFFICE.

WILLIAM KETCHUM JONES, OF WICHITA, KANSAS.

COMBINATION-SUIT.

1,145,771.

Specification of Letters Patent. Patented July 6, 1915.

Application filed May 5, 1914. Serial No. 836,458.

To all whom it may concern:

Be it known that I, WILLIAM K. JONES, a citizen of the United States, and a resident of Wichita, in the county of Sedgwick and State of Kansas, have invented a new and Improved Combination-Suit, of which the following is a full, clear, and exact description.

The jacket or body of the garment is connected integrally at the front with the trousers and the latter have a sanitary drop flap at the back and the jacket is provided with a depending flap adapted to overlie and cover said drop flap, together with the pockets with which the drop flap is provided, the depending flap being secured to and over the pockets by buttons attached to the latter.

In the accompanying drawing: Figure 1 is a front perspective of the combination suit as applied to the person of a wearer. Figs. 2 and 3 are rear perspective views showing the jacket flap in position over the drop flap and pockets and buttoned to the latter.

A jacket or coat A and trousers B are integrally connected at the front and the jacket is open along the front median line to permit the wearer to conveniently don or remove the suit. Buttons C normally close the front. The back of the trousers B is provided with a sanitary drop flap having at the sides buttons G' adapted to engage button holes formed on the sides of the trousers B'. The back of the latter is provided with pockets K having buttons I se-

cured to their outer sides. The back of the jacket A is provided at its lower end with an integral covering flap H, extending a distance below the waist line of the drop flap D so as to cover the upper portion of the latter and overlie the pockets K; and the said covering flap H is provided at the lower corners with button holes H', H'', as shown in Fig. 2, said button holes being adapted to receive buttons I on the pockets. Thus the said buttons hold the covering flap H normally down, as shown in Fig. 2 and this arrangement prevents the contents of the said pocket in falling out; at the same time protecting them from entrance of dust, etc.

Having thus described my invention, I claim as new and desire to secure by Letters Patent:

The improved garment comprising a jacket, trousers integrally connected therewith at the front and having a sanitary drop flap provided with exterior pockets, the said jacket being provided at the back with a covering flap adapted to overlie the drop flap and pockets, and buttons securing the drop flap to the pockets detachably, as described.

In testimony whereof I have signed my name to this specification in the presence of two subscribing witnesses.

WILLIAM KETCHUM JONES.
